AUTOMATIC SAFETY CATCH

Frank Vogel, Philadelphia, Pa., assignor to
Albert H. Reef, Philadelphia, Pa.

Application November 20, 1948, Serial No. 61,189

6 Claims. (Cl. 24—158)

1

My invention relates to a new and useful automatic safety catch for use on brooches, pins and other articles, especially jewelry, which are pinned to wearing apparel or other items and said catch is to prevent the accidental disengagement of the pointed bar or fastening pin from its keeper.

One object of the invention is to provide a safety catch having smooth curvilinear exterior surfaces giving a highly streamlined appearance thereto and which will not readily snag wearing apparel.

Another object of this invention is to so position the spring relative to the sliding latch that the pressure or force of said spring is applied closer to the center of the device thus eliminating the "drag" due to a tendency of tilting the latch in its housing or the body of the safety catch in many devices of this general character.

Another object of the present invention is to provide a sliding latch member having inclined side edges and a generally triangular shaped opening to permit the utilization of a narrower base design.

Another object of the invention is to construct the latch member with a convex bottom edge, thus reducing surface contact with the body or housing thereby permitting smoother operation.

Another object of the invention is to provide a tapered curvilinear body to hold a spring latch member, said body having a convex inner bottom surface to be engaged by a restricted portion of the bottom edge of said latch member thereby eliminating gouging and permitting easy sliding movements.

Another object of the invention is to construct a safety catch including a body member housing a sliding latch member, the companion member engaging bottom surface of one of the members being convexly curved to eliminate gouging during operation of the latch member.

A further object of this invention is to construct the body member with integral latch stops which also function as guards to prevent solder entering the latch chamber during the time the safety catch is being attached to the jewelry item.

A still further object of the present invention is to provide a safety catch including a partially split body member to hold a sliding latch member, said body member capable of being bent open to receive the latch member and when closed forming a latch holding chamber from which the latch cannot be accidentally displaced.

With the above and other objects in view this 55

2

invention consists of the details of construction and combination of elements hereinafter set forth and then designated by the claims.

In order that those skilled in the art to which this invention appertains may understand how to make and use the same I will describe its construction in detail, referring by numerals to the accompanying drawing forming a part hereof, in which—

10 Fig. 1 is a side view of the safety catch, showing the position of a fastening in dotted lines when it first enters the catch.

Fig. 2 is a top view of the same.

Fig. 3 is a face view of the latch.

15 Fig. 4 is an end view of the body looking at the right hand side of Fig. 1.

Fig. 5 is a side view, similar to Fig. 1, of a modified form of body but embodying the partially split feature.

20 Fig. 6 is an end view thereof looking at the right hand side of Fig. 5.

Fig. 7 is a section on the line 7—7 of Fig. 1.

Fig. 8 is a side view of the body in Fig. 4 spread open to receive the latch member during assembly.

25 Fig. 9 is a view of an item of jewelry showing my improved safety catch mounted thereon.

In carrying out my invention as herein embodied 10 represents the body member of the safety catch which is formed as a casting or forging. This body has a pin receiving slot 11 which divides said body into substantially two halves or hemispheres 12 and 13 but said slot 11 terminates short of the restricted base 14.

30 35 Through the body, crosswise of the slot, is formed an aperture 15 to receive the sliding latch, to be presently described, and from the top wall of said aperture to the exterior top surface of the body extend open seams 16, one in each of the hemispherical parts of the body. The body is left or formed in an open position at the seams, as shown in Fig. 8 so as to receive the sliding latch prior to the body being closed as shown in Fig. 4. The aperture 15 projects downwardly into the base of the body below the portals of said aperture to provide integral latch stops 17, one at each portal of the aperture 15 and form the latch chamber.

35 40 The exterior surface of the body 10 is made up of a multiplicity of blending curves and is of a general global shape when viewed from the end, Fig. 4, thereby providing a rounded top surface 18 inclined both sideways and crosswise and finally tapering, at 19, to the circular restricted base 14. The hemispherical portion 12 has an inwardly

inclined convexly curved surface 20 leading to the contiguous side wall of the slot 11 while the hemispherical portion 13 has a long beveled surface 21 leading to the other side wall of said slot. The beveled surface 21 terminates below the inclined surface 20, but together they form a mouth or entrance for the slot 11.

As previously stated, a latch member 22 is slidably mounted in the aperture 15, constituting the latch chamber, and said latch member is formed from flat stock of generally V-shape providing divergent legs 23 and 24 having inclined outer side edges 25, Fig. 3, and a convex bottom edge 26 so there will be a limited contact with the bottom of the aperture 15 or latch chamber to avoid a gouging effect which often occurs between the flat surfaces of coacting members when one of such members tilts during sliding movements. The substantially triangular shaped opening 27 which receives the fastening pin 28 of the article of jewelry 29, Fig. 9, permits of the narrow construction or design of lower end of the latch member. Projecting from the upper end of the leg 23 into the opening 27 is a beak 30 having a convex upper surface 31 which, preferably, blends with or projects as a continuation of the curved surface 20 of the body. The underneath edge 32 of the beak is slightly concave, blending into an arc 33 of a smaller circle, the latter connecting with a convergent inner edge 34 of the leg 23. The edge 34 joins with a concaved edge 35 at the bottom of the opening 27 and said concaved edge 35 connects with the slightly angular straight inner edge 36 of the leg 24. From the upper outer side edge of the leg 24 projects a tailpiece 37 to provide the desired or proper length of surface at the upper end of the leg 24 to positively retain engagement with the body hemisphere 13 within the aperture 15. Also from the outer side edge of the leg 24 approximately midway its height projects an angular arm 38 extending obliquely upwardly and outwardly so that its upper end terminates substantially in the same horizontal plane as the legs 23, 24. The terminal end of said arm 38 is reduced to provide a neck 39 and shoulders 40. The neck preferably extends in a horizontal direction, with the shoulders at right angles thereto, and after a small coil spring 41 is placed on the arm 38, a washer 42 is assembled on the neck 39 to abut the shoulders 40, and the terminus of the neck is peened or riveted to form the head 43 which will hold the associated parts together. As the inner end of the spring 41 engages the body 10 substantially midway the height of the latter the force or pressure of the spring is more evenly distributed between the top and bottom ends of the device, thus insuring a free sliding movement of the latch since it is less likely to become cocked within the body.

In Figs. 5 and 6 I have illustrated a slightly modified form of body 10a to hold the same type of latch member described above. This body member 10a is fashioned from a flat piece of material bent into proper form with the seams 16a at the top. The fashioning of the sheet metal into the body formation provides the latch receiving aperture 15a and the inside surface of the bottom wall may be convexly curved lengthwise of the aperture, as at 26a, for the same purpose as the convex edge of the latch member 22, which convex edge may be straight when used with the convex surface of the body bottom wall.

To prevent the latch member being expelled from the body at least one stop 17a is bent from

a suitable portion of the body material and disposed across a portal of the aperture 15a. By disposing such a stop across each portal the movements of the latch member can be limited in both directions and by positioning the stops so they practically close the lower ends of the portals said stops will function as guards to prevent solder entering the aperture while the catch is being secured to an item of jewelry.

An open slot 11a is formed in the body crosswise of the aperture 15a and divides said body into two approximate halves 12a and 13a, and the inner side edge of the part 12a has a short beveled portion 20a leading to the slot while the inner side edge of the part 13a has a long beveled portion 21a leading to said slot. These beveled edges or portions constitute a mouth or entrance for the slot 11a. Both of the end edges 19a of the body taper or converge towards the base portion of said body, as depicted in Fig. 5, to provide a restricted base portion making it possible to mount the safety catch on relatively narrow items of jewelry.

In attaching such a device to the item solder is generally used and even when great care is employed some of the solder may flow into spaces such as the aperture 15, but by providing guards in the form of the stops 17 this possibility is reduced to a minimum.

It is to be particularly noted that the latch member 22 is positioned to one side of the center of the body thus, in effect, large and small portions of said body are located on opposite sides of the latch member and the smaller portion is positioned towards the pivot point of the pin 28 so that said latch member will engage said pin 28 back of the sharpened end and still said sharpened end will be within the confines of the body.

Because of the beveled inside edges of the entrance to the slot 11 the pin 28 can be easily entered, and due to the convex upper edge of the beak in conjunction with the opposed beveled edge of the body, the latch member is readily retracted to permit the pin 28 to enter the keeper portion of the opening 27 and the lower part of the slot 11. After the pin 28 passes the beak it will engage the concaved underneath edge of the beak and assist in retaining the sliding latch member in a retracted position in connection with the action of the spring 41.

Of course I do not wish to be limited to the exact details of construction herein shown and described as these may be varied within the scope of the appended claims without departing from the spirit of my invention.

Having described my invention, what I claim as new and useful is:

1. An automatic safety catch comprising a body having a pin receiving transverse slot extending part way into said body from the top thereof and further provided with an open ended aperture crosswise of and communicating with said slot, the body having open seams leading to said aperture to permit separation of the body parts for access to the aperture other than through the open ends, a latch member slidably mounted in the aperture and comprising a pair of upwardly divergent legs, a beak projecting from the upper end of one of said legs into the space between them, a tailpiece projecting outwardly from the upper end of the other of said legs, an integral arm projecting obliquely upwardly and outwardly from said other leg at a point approximately midway the height of the

latch, a spring on said arm having one end in engagement with the body, and means mounted on the outer end of said arm to hold the spring in place and act as an abutment for the other end of said spring.

2. A safety catch including a downwardly tapering body of bendable material having a latch receiving aperture extending through said body from side to side, said body being closed at the bottom and having a normally closed seam at the top, the parts of the body on opposite sides of the seam being partially separable for assembly of a latch which is held in place after the body parts are closed, said body having a pin receiving slot crosswise of the aperture open at the top of the body and communicating with the aperture and the surfaces of the body being curved to meet the side walls of said slot, a V-shaped latch slidably mounted in the aperture and comprising a pair of upwardly divergent legs forming a substantially triangular shaped opening, a beak projecting from one of said legs into the opening, said beak having a convex upper edge and a concave lower edge, a tailpiece projecting outwardly from the upper end of the other leg to provide an extended bearing surface, and an arm projecting obliquely upwardly from the outer side edge of said other leg at approximately midway the height of said other leg, said arm terminating in a neck with shoul-

ders at the base thereof, a spring on said arm with one end engaging the body, and means on the neck engaged by the opposite end of the spring, said means resting against the shoulders and held in place by a head formed from the neck.

3. The structure according to claim 2 wherein the body is of curvilinear formation and the bottom is circular.

10 4. The structure according to claim 2, in combination with a stop integral with the body at the end of the aperture adjacent the position of the latch arm.

15 5. The structure according to claim 2, in combination with stops integral with the body at both ends of the aperture and closing the lower portion of said aperture.

6. The structure according to claim 2 wherein the latch has a convex bottom edge.

FRANK VOGEL.
